TOY PARACHUTE

Elvy Kalep, New York, N. Y.

Application February 25, 1943, Serial No. 477,027

2 Claims. (Cl. 46—86)

This invention relates generally to toy parachutes, but more specifically to means of projecting such toy parachutes from external and suspended position.

The main object of the invention resides in the provision of mechanical means for propelling one or more toy parachutes suspended from an exposed rod or other support whereby said parachute or parachutes are displaced from suspended position to elevated and free positions from which they descend under the influence of gravity in a manner simulating the descent of real parachutes.

Another object of the invention resides in the provision of means for slidably mounting each umbrella portion of the parachutes to the rod or support from which the parachutes are thrown or propelled whereby displacement is easily effected on application of direct or indirect forces such as impact, recoil and centrifugal forces.

Another object of the invention resides in the provision of a toy game wherein a plurality of toy parachutes are capable of being projected into the air in consecutive order, said parachutes being capable of descending from different positions and landing at spaced points and at different times to simulate a paratroop attack on enemy territory.

A further object of the invention is to provide a game of the above nature which is simple in construction, durable in use, economical to manufacture, and sturdy in construction.

These objects and other incidental ends and advantages of the invention will hereinafter appear in the progress of the disclosure and as pointed out in the appended claims.

Accompanying this specification are drawings showing preferred forms of the invention, wherein corresponding reference characters designate corresponding parts throughout the several views and wherein:

Figure 1 is a view in perspective showing a plurality of toy parachutes suspended on a rod before propulsion.

Figure 2 is a view in perspective showing a toy parachute in its descent toward the ground.

Figure 3 is a top view in elevation of the umbrella portion of Figure 2.

Figure 4 shows two fragmentary and transverse sectional views of two types of securing means taken along the vertical plane of the umbrella portion for engaging the toy parachute to the propulsion rod.

Figure 5 is a view in perspective of a modified

form of a propulsion rod in the form of a gun or pistol in association with toy parachutes.

Figure 6 is a side view in elevation of Figure 5, partly in section, showing the mechanism for the propulsion of the toy parachute.

Figure 7 is a view in perspective of another modified form of the invention.

Figure 8 is a fragmentary sectional view of the device shown in Figure 7.

Figure 9 is a view in perspective of a third modified form of the invention.

Figure 10 is a sectional view of Figure 9 taken along the longitudinal axis thereof and omitting the toy parachutes.

Figure 11 is a fragmentary and an enlarged sectional view of the end portion of the propulsion means shown in Figure 9.

Figure 11a is a view similar to Figure 11 showing the actual propulsion of the toy parachutes from the propulsion rod.

Figure 12 is a fragmentary view in top elevation showing a spring on the end of the propulsion rod.

In accordance with the invention and in accordance with the preferred forms shown in the drawings, the embodiment in Figures 1, 2, 3, and 4 presents one or a plurality of toy parachutes having the conventional fabric or umbrella portions 10 in association with shrouds 11 secured to the fabric at preferably the reinforced perimeter thereof as by passing the upper ends of each shroud 11 through an opening therein and tying with a knot as indicated by numeral 12. The lower ends of the shrouds 11 converge for attachment to a weighted member such as a toy doll 13, the points of attachment between the lower ends of the shroud cords and the doll being preferably at the rear of the doll head.

As shown in Figure 1, the perimeter of the fabric 10 may be scalloped for purposes of serving as a guide for the spacing of the points of attachment between the upper ends of the shrouds 11 and the perimeter of the fabric. In the center of fabric 10 may be a ring member

45 15 preferably made of fiber, at the lower end of which is provided a fastening means 16 whereby said ring member 15 may be secured to the fabric 10 by piercing the upturnable ends 17 and 18 of the fastening member through said fabric 10 and then separating these members as best shown in Figure 4. Instead of the use of ring member 15, a loop 15a of cord or like material may be used penetrating openings 15b and 15c in the fabric 10 and then having the free ends of the loop tied into a knot 15d inside the fabric 10.

In Figure 1 a plurality of toy parachutes are generally designated by A, B and C freely suspended on a rod 19 through ring members 15. The toy parachutes A, B and C are in adjacent relationship and are propellable from rod 19 by imparting to the latter a circular motion in the vertical plane or by bowing the rod 19 and releasing the same. Such motion causes the toy parachutes A, B and C to slide off at a tangent to the movement of rod 19, parachute A flying off first, and thereafter parachutes B and C in consecutive order. Following such propulsion, the parachutes are displaced into the air at separate points and begin to descend from different elevations and from staggered positions, thereby giving the illusion of a paratroop attack.

In Figures 5 and 6 is shown mechanical means of propelling parachutes A, B and C. Thus, propulsion rod 19 is secured by an outer sleeve 21 to a handle 20, the latter simulating the butt of a pistol. Sleeve 21 preferably frictionally engages rod 19 while the sleeve is suitably secured to the top edge of butt 20. A movable ramming member having a cylindrical section 22 at the forepart and a continuing rear part 23 is provided to ride along sleeve 21. The rear part 23 has a portion of the lower wall cut away from the junction with the forepart 22 and the forward portion thereof is provided with a notch 24 which is adapted to engage a dowel or pin 25 secured at the upper end of the front wall of butt 20. At the front edge of butt 20 is another notch 20a disposed below the line of attachment between sleeve 21 and the upper edge of butt 20. Secured in notch 20a is a rubber band or elastic 26 which engages notch 27a on edge 27 of portion 23 of the ramming member. Extending across the inner end of portion 23 and adjacent edge 27 is a dowel 28 which abuts dowel 25 when the ramming member is released.

The ramming member when in shooting position and drawn against the tension of elastic 26 as shown in Figure 5 is released by pushing the same upwardly with the fingers so that dowel 25 is freed of notch 24. At such time, the distended rubber band 26 forces the ramming member to travel along sleeve 21, the outer edge of portion 22 giving the ring members 15 of parachutes A, B and C a sudden blow thereby propelling them from the end of rod 19. It is to be observed again that the displacement of the ramming member is limited by the engagement between dowels 28 and 25, so that the ramming member is never separated from the sleeve 21. To reload, the ramming member is drawn backwardly against the tension of elastic band 26 until dowel 25 engages the notch 24. Before or after "loading," parachutes A, B and C are inserted through rings 15 at the end of rod 19.

Figures 7 and 8 present another embodiment of means for mechanically propelling one or more parachutes into the air by the use of a bowed member. Thus, rod 19 is secured to a sleeve member 31 having an extension or grasping portion 33 at one end. A transversely disposed dowel 32 penetrates both the sleeve 31 and the rod 19 adjacent member 33, and an outer bearing ring 30 for sleeve 31 having portions 29, 29 comprising a bowable member secured thereto

on opposite sides, is used for guiding the movement of sleeve 31. Portions 29 are flexed by means of an elastic member 34 engaging the ends 29' and the lower end of the sleeve 31 adjacent grasping member 33. The parachutes A, B and C are mounted on the end of rod 19 which projects from sleeve 31. The player grasps either portion 29 and pulls back sleeve 31 at member 33 against the tension of the elastic 34 while the elastic is secured in ends 29' and the end of sleeve member 31. On releasing the member 33, the sleeve 31 is propelled forwardly and guided through bearing 30 and is stopped when dowel 32 on sleeve 31 hits the inner end of bearing 30. Such impact causes the propulsion of the parachutes A, B and C off rod 19 into the air.

In a further embodiment of the invention as shown in Figures 9, 10, 11 and 11a the parachutes A, B and C are propelled off rod 19 by means of a crank lever. Thus, rod 19 is secured to a lever 36, the rod having secured to the outer end thereof as by a spur 41a a flexible leaf spring 41 which has a protruding and an upwardly curved end portion to prevent the normal release of the parachutes A, B and C. When lever 36 is made to rotate at a predetermined acceleration, centrifugal force causes the parachutes to fly off the spring 41 and thereby straighten the same as shown in Figure 11a. The lever 36 is provided with a handle 37 having a reduced neck portion 39 mounted within an opening 38 at the end of lever 36. An assembling member 40 having any attaching means such as a shank 41b is secured to the reduced neck portion 39 from the outer surface of lever 36 whereby the lever 36 may be rotated about handle 37 at right angles thereto. During rotation of lever 36 about handle 37, means may be provided to produce sounds simulating an airplane motor such as the use of a pawl 42 secured to handle 37 which intermittently engages one or more dowels 43 projecting from the outer face of lever 36.

I wish it understood that minor changes and variations in the preferred embodiments of the invention may be resorted to without departing from the spirit of the invention and the scope of the claims.

I claim:

1. A propellable toy parachute comprising a parachute fabric portion having a load secured thereto and carrying a member at the top thereof, a rod slidably engageable with said member and serving as a guide therefor whereby the parachute is freely suspended from said rod and propellable into the air, means to propel said parachute portion and load into the air from said rod.

2. A propellable multi-parachute toy comprising a plurality of independent parachute fabric portions having loads secured to each, an attaching member secured to the top of each fabric, a rod to which each of the fabric portions at the attaching member is slidably and detachably engageable and serving as a guide therefor whereby each parachute is freely suspended from said rod and consecutively propellable into the air, means to propel said parachutes consecutively into the air from said rod.

ELVY KALEP.
